UNITED STATES PATENT OFFICE

CHARLES F. VANCE, OF WINSTON-SALEM, NORTH CAROLINA

WOODWORKING MACHINE

Application filed October 23, 1931. Serial No. 570,559.

This invention relates to a machine for joining sections of wood together and more especially to a device for cutting tongues and grooves in the ends of pieces of material so that these pieces of material can be glued together to form strips, planks, and the like of any desired length and thereby utilizing short pieces of wood for providing pieces of great length and of equal strength as pieces of one continuous plank or the like, thereby utilizing waste pieces of material for forming planks of various lengths to be used for various purposes.

An object of this invention is to provide a machine in which a plurality of pieces of plank, wood, strips and the like can be clamped into position and all of the ends cut smoothly in a straight line, and while still in the machine these pieces of wood may be passed along a cutter head whereby a plurality of grooves can be cut in the ends of the pieces so that the pieces can be removed and joined together by gluing and the like to form a piece of material of any desired length, depending upon the number of pieces used and the length of the pieces.

Some of the objects of the invention having been stated other objects will appear as the description proceeds when taken in connection with the accompanying drawings, in which—

Figure 1 is a side elevation of the machine;

Figure 2 is an end view of the machine looking from the right hand of Figure 1;

Figure 3 is a top plan view of the machine;

Figure 4 is a cross sectional view looking downward and showing a portion of the lower part of the machine;

Figure 5 is a side elevation, looking from the lower side of Figure 4;

Figure 6 is an enlarged detail view of one of the clamps;

Figure 7 is a longitudinal sectional view taken along the clutch shaft and associated parts;

Figure 8 is a cross sectional view taken along the line 8—8 in Figure 2;

Figure 9 is an end view of the upper por-

tion of Figure 6 and looking from the left-hand side thereof;

Figure 10 is an enlarged view of the other of the clamping means for holding the top edges of the pieces of material in position;

Figure 10a is a view of the product of the machine;

Figure 11 shows a modified form of operating means for the vises;

Figure 12 is a sectional view taken along the line 12—12 in Figure 11;

Figure 13 is a view similar to Figure 12 but showing the valve in a different position.

Referring more specifically to the drawings, the numeral 10 indicates the base portion of the machine having the upwardly extending portion 11 and the top portion 12, the top portion supporting an electric motor 13 having secured thereon a cut-off saw 14 with a shield 15 around the saw, said motor having a shaft 16 on which a pulley 17 is mounted with a belt 18 passing around said pulley and passing around also an enlarged pulley 19 secured on sleeve 20 rotatably mounted on stud shaft 20a, and on this sleeve is also secured a pinion 21 meshing with a gear 22 (see Fig. 7) which is keyed on a sleeve 23 loosely mounted on shaft 24. The shaft sleeve 23 is mounted in a bearing 23a and shaft 24 is mounted in a bearing 24a.

Secured on shaft 24 is a sprocket wheel 25 on which is mounted a sprocket chain 26 which passes over enlarged sprocket wheel 27 secured on shaft 28 which shaft 28 has secured thereon a pinion 29 which meshes with a gear 30 mounted on shaft 31 which shaft 31 penetrates the portion 11 and has its other end mounted in bearing 32, and on the end of this shaft is a wheel 33 which has a roller 34 mounted on a stud bolt 35 which roller is mounted for movement (see Fig. 1) in slot 36 of rocking quadrant 37 pivotally mounted as at 38 on the portion 11, and the upper end of member 37 has the curved segmental gear portion 39 for engagement with rack 40 on sliding table 41 mounted on a trackway composed of members 42 and 43 (see Fig. 2). Shaft 38 is mounted in a support 38a secured to side of portion 11.

Shaft 28 is mounted in bearings 45 and 46 secured to stand 11 of the framework of the machine.

Sliding table 41 has a portion 50 secured 5 on the upper side thereof by means of stud bolts 51. This member 50 projects upwardly and has the horizontally projecting portion 53 and the downwardly projecting portion 54, the portion 53 having the threaded bolt 10 55 with hand wheel 56 thereon and being threadably mounted in the portion 53 and having on the lower end thereof (see Fig. 10) an enlargement 60 having a groove 61 therein for the reception of clamping member 62, 15 said portion 60 having a lower enlargement 63 fitting into a groove 64 in said clamp member 62, the lower edge of this clamp member 62 being sharpened to grip the upper edges of the pieces of material placed into the 20 clamping device.

The upwardly projecting portion of member 50 has two projections (see Fig. 2) indicated by reference characters 65 and 66 having stud bolts 67 and 68, respectively, mounted 25 therein which are adapted to engage the upper edge of a board 68 adapted to remain at all times in the clamp and to be sawed off at the first sawing operation of a bunch of pieces of wood in the clamp to form a support for the other pieces of wood to be sawed and to prevent the rearmost wood from having imparted thereto a roughened edge due 30 to engagement with the saw and cutter head.

Also mounted on sliding table 41 is another clamping member indicated more clearly in Figure 6, comprising a base plate 35 secured on table 41 by any suitable means such as stud bolts 71 and from this portion 70, upwardly projecting portions 72 and 73 40 are provided and integral with portions 72 and 73 and spanning the distance therebetween is the hollow portion 74 having slidably mounted therein screw threaded member 76 having the squared enlargement 77 thereon 45 for guiding the same and preventing turning movement. On the exterior of said member 76 is provided a bevel gear 78 which is threadably mounted on the threads 79 of member 76, and the end of member 76 has loosely secured 50 thereon clamping member 80 having the serrated or roughened face 81 for engaging the sides of pieces of material held in the clamp for the sawing and grooving operation.

55 Meshing with bevel gear 78 is another gear 82 which is mounted on a shaft 83 which is rotatably mounted in bearing portion 84 projecting upwardly from plate 70, and on this shaft is a hand wheel 86 having a handle 87 60 for imparting rotation thereto.

Shaft 20a is supported at its outer end by a bracket 20b.

Cutter head 127 has a guard 128 therearound, and also a guard 128a secured to 65 table 41.

By referring again to Figure 7 it is seen that sliding member 23 also has keyed thereon a portion 90 of a clutch mechanism, said portion 90 having a cavity 91 therein for reception of the sloping cone-shaped face of member 92 forming the other portion of the clutch which member is keyed for sliding movement on shaft 24 by means of key-way 93 and is adapted to slide on shaft 24 but to rotate therewith at all times. Secured on shaft 24 is a cuff 94 having a compression spring 95 between said cuff and said member 92 for normally forcing the cone-shaped member 92 into the cavity 91 for locking shaft 24 and sleeve 23 for rotation together, but means are provided for releasing the clutch, said means comprising a member 100 which is forked at its lower end and is slidably mounted on shaft 101 and at its upper end is secured to a connecting rod 102 by means of a bolt 103, said connecting rod 102 being connected to an arm 104 (see Figs. 1 and 2) mounted on vertically disposed rotatable shaft 105. Shaft 105 is mounted in bearings 106 and 107 at its lower and upper ends respectively, and also has an arm 108 thereon adapted to engage upwardly projecting portion 109 of foot lever 110 secured in bracket 111 on base plate 10. By referring to Figure 3, it is seen that the upper end of shaft 105 has secured thereon a lever 115 and on said lever is pivotally mounted another lever 116 which lever is normally pulled to the position shown by tension spring 117 and is adapted to engage a projection 118 on the side of table 41.

With the carriage 41 in position for the material in the vises being disposed between the cutter 127 and the saw 14 and the machine started, operator will seize lever 115 pivotally mounted on lever 116 and move its forward end out of the path of projection 118 on the carriage. When the carriage travels to the left in Figure 3 until projection 118 passes the forward end of lever 116, the operator will relieve lever 116 and the carriage will move the material in the vises past the saw and the carriage will then reverse its direction of travel and will slip past end of lever 116 without affecting lever 115. When the carriage has moved all the way to the right in Figure 3 and has reversed its travel and moved back to the position shown in Figure 3, projection 118 will strike the forward end of lever 116 and this will move lever 116 to the left in Figure 3 and will move lever 115 which will turn shaft 105, and arm 104 will pull connecting rod 102 to disengage the clutch portion 92 from portion 90 and the driving connection to the carriage 41 will be disconnected from sleeve 23.

By referring to Figures 1 and 3, it is seen that a cutter head and housing is provided for cutting the grooves in the ends of the material forming the tongues and grooves

for joining the pieces of material together. On the lower side of the upper portion 12 and at one side thereof is secured an electric motor 125 whose shaft 126 projects upwardly thru the upper portion of the machine indicated by 12 and has thereon a cutter head 127 which has a plurality of knives 128 mounted therein, and these knives have a plurality of teeth 129 closely related to each other similar to the teeth of a circular saw but of a peculiar formation to cut a groove as shown in Figure 10. These cutters 128 are secured in the cutter head 127 by any suitable means.

Power is supplied to the two electric motors by any suitable form of electric conductor, not shown, which passes into the machine and thru switch 140 and a cable 141 leads thru a box 142, and from box 142 a cable 143 is led into motor 125, and a suitable cable 145 leads from the other side of box 142 from that shown in Figure 1 and goes to motor 13 so that both motors will start and stop at the same time.

In order that the tongues 150 fitting into grooves 151 may be such as to cause the edges of proximate pieces to be in alinement, a suitable block, not shown, may be placed beneath alternate sets of pieces grooved, so that one piece taken from one set of blocks will fit with a piece taken from another set to form a straight edge when the two pieces are secured together at their ends.

In Figures 11 to 13 inclusive, I show a different form of holding means for the boards and instead of having clamp members 50 and 70 for operating the clamping members 162 and 80, I have an inverted U-shaped bracket 160 secured to table 41 and a cooperating bracket 161, bracket 160 having an upwardly projecting leg 162 and between member 161 and 162 a cylinder 163 is provided having a piston 164 therein with a connecting rod 165 on which a clamping member 80 is mounted.

On top of U-shaped member 160 is mounted a cylinder 165 by means of bolts 166 and a cap plate 167, and a piston 168 is mounted in cylinder 165 and has a connecting rod 169 whose outer end is secured to knife clamp 62. Also on table 41 I secure a valve 170 which has an air supply pipe 171 leading thereto which is connected to a suitable source of compressed air—not shown—by any suitable means such as a rubber hose, not shown. This valve 170 has mounted therein a rotor 172 having cavities 173 and 174 therein and pipes 175 and 176 are connected to said valve housing and communicate with the interior thereof. An exhaust port 178 is provided in said valve housing 170. Pipe 175 is connected to the remote end of cylinders 165 and 163 and in the position shown in Figure 13, compressed air is admitted to the said cylinders to force the clamps 62 and 80 into clamping position.

When the clamps are moved to clamping

position air is allowed to escape from in front of pistons 164 and 168 thru pipe 176 which is connected to the other ends of said cylinders. This air escapes thru port 178 with the valve in the position shown in Figure 13. 70

When the clamps are to be released from clamping position, the valve rotor 172 is turned to the position shown in Figure 12 and compressed air is forced through pipe 176 which forces the pistons to the position shown in Figure 11 and the air on the other side of said pistons is allowed to escape thru pipe 176 out thru port 178 as shown in Figure 13.

In the drawings and specification, there has been set forth a preferred embodiment 80 of the invention and although specific terms are employed, they are used in a generic and descriptive sense only and not for purposes of limitation, the scope of the invention being set forth in the appended claims. 85

I claim:

1. In a woodworking machine for forming tenons in the ends of a plurality of pieces of wood and similar material, a cut-off saw, a cutter head for forming grooves and tenons 90 in the ends of said pieces, a carriage, means for clamping the pieces in position in said carriage, means for moving the carriage in one direction for feeding the pieces past the saw, means for reversing the direction of 95 travel of the carriage to feed the material again past the saw and past the cutter head, means for again reversing the travel of the carriage to feed the material back by the cutter head and back toward the saw and 100 means for automatically stopping the feeding means before the pieces again reach the saw.

2. In a woodworking machine for forming a plurality of transverse grooves in the ends of pieces of material, a framework, a slidable table mounted on top of said framework, clamping means on said table for said pieces, a motor driven saw on said framework, a motor driven cutter head on said framework, means for moving the table back and forth 110 on said framework to first present the pieces to the saw and reversing the travel of the table to present the pieces to the cutter head and then reversing the travel of the table to move the pieces again past the cutter head 115 and means for automatically stopping the table before the material again reaches the saw.

3. In a machine for forming grooves in the ends of a plurality of blocks of material, 120 a cut-off saw, a cutter head for cutting grooves in the ends of said blocks, a slidable table, means on the table for clamping said blocks in position, means for moving said table with relation to said saw to saw off a portion of the ends of said blocks, means for reversing the direction of travel of said table to move the blocks again past said saw and towards said cutter head for forming grooves 125 in the ends of said blocks, means for again 130

reversing the direction of travel of said table to move the blocks again past the cutter head and towards said saw, and means for automatically stopping the table when it has reached a given point between the cutter head and the saw.

4. In a machine for forming grooves in the ends of a plurality of blocks of material, a cut-off saw, a cutter head for cutting grooves in the ends of said blocks, a slidable table, means on the table for clamping said blocks of wood in position, means for moving said table past said saw to saw off a portion of the ends of said blocks, means for reversing the direction of travel of said table to move the blocks again past said saw and towards said cutter head for forming grooves in the ends of said blocks, means for again reversing the direction of travel of said table to move the blocks again past said cutter head, and means for automatically stopping the table when it has reached a given point between the cutter head and the saw.

5. In a machine for cutting grooves in the ends of pieces of wood whereby the same may be joined together, a framework, a table slidably mounted on said framework, a plurality of means for clamping a plurality of pieces of wood on said table, a cut-off saw, a cutter head having teeth therein for forming grooves in the ends of the pieces of wood, means for reciprocation of said table to cause the pieces to pass the saw, means for reversing the travel of the table to move the pieces again past said saw into engagement with the cutter head to cut the grooves in the pieces of wood, means for again reversing the travel of the table to cause it to move the pieces of wood again past the cutter head and toward the saw, and means for automatically arresting the travel of the table before the pieces again reach the saw.

6. A wood working machine having in combination a cut-off saw and a groove-forming cutter head spaced from each other, a slidable table disposed on one side of said saw and cutter, means for securing pieces of wood on said table and means for moving the table to present the wood to the saw and then reversing the travel of the table to present the pieces to the cutter and then reversing the travel of the table to move the pieces again past the cutter and to move the pieces again toward the saw.

55 7. In a wood working machine, a cut-off saw, a groove-forming cutter head, a table slidable past the saw and cutter head, a plurality of clamps mounted on said table adapted to receive pieces of wood, means for moving the table first by the saw, then reversing the direction of the travel of the table to move it by the cutter head, and then again reversing the direction of travel of the table to again move it towards the saw, and means for automatically stopping the

travel of the table before the pieces of wood are again presented to the saw.

8. In a woodworking machine for forming tenons in the ends of suitable stock, a framework, a carriage mounted for sliding movement along said framework, a cut-off saw mounted on said framework and having a horizontally disposed axis, a tenon-forming cutter head mounted in said framework and having a vertically disposed axis, a rack disposed on the lower surface of said carriage, a reciprocating quadrant meshing with said rack, means for clamping said stock in said carriage, means for reciprocating said quadrant to cause the carriage to move the stock past the saw, then reversing the direction of travel of the carriage to move the stock again past the saw and to move the stock past the cutter head to form tenons in the end of the stock and to then reverse the travel of the carriage to move the stock again past the cutter head and towards said saw, and means for automatically stopping the travel of the carriage before the stock is again presented to said saw.

In testimony whereof I affix my signature.
CHARLES F. VANCE.
